PERCUSSION TRIP DEVICE FOR ELECTRIC CIRCUIT BREAKERS

Georges Balachowsky, Paris, France, assignor to
General Electric Company, a corporation of
New York

Application November 4, 1947, Serial No. 734,020
In France February 6, 1947

4 Claims. (Cl. 200—106)

1

My invention relates to actuating means for electric apparatus and, more particularly, to the control of the tripping function of electric circuit breakers by means of an elastic impulse wave transmitted to the tripping mechanism through an insulating rod.

In high voltage electric circuit breakers, it is necessary to separate the high voltage conductors from the control system by a distance which is adequate to isolate the high voltage conductors from the control system. In circuit breakers having retractable contacts which are biased to the open position and which are held closed by a suitable latching mechanism, it has been the practice to impart a tripping force to the latch mechanism by bodily moving a relatively long insulating member into engagement with the latch mechanism by means of energy supplied to the rod at a point removed from the high voltage conductors associated with the breaker itself. Where the breaker voltage rating is relatively high, it is necessary to use a relatively long tripping rod constructed of insulating material. The mass and inertia of such long insulating rods may be so great as to impede unduly and to slow-down the tripping operation of the circuit breaker.

Accordingly, a principal object of my invention is the provision of a device for imparting actuating force to electric apparatus wherein a mechanical impulse is transmitted from a relatively remote point to a member disposed in cooperative relationship with the apparatus to be controlled.

Another object of my invention is the provision of a relatively long rod of insulating material interposed between the tripping apparatus of an electric circuit breaker and a source of control energy wherein the source of control energy is utilized to impart motion to a member which in turn collides with one end of the insulating rod to set-up therein a high speed impulse for use in imparting a controlling force to the circuit breaker.

Still another object of my invention is the provision of a high speed control system for an electric circuit breaker of a relatively high voltage rating wherein the relatively low voltage control circuit is removed from the high voltage conductors by an adequate isolating distance.

A still further object of my invention contemplates the transmission of a mechanical impulse to the controlling mechanism of an electric circuit breaker through a substantially stationary insulating rod.

Further objects and advantages of my invention will become apparent as the following description

proceeds and the features of novelty which characterize my invention will be pointed out with particularity in the claims annexed to and forming a part of this specification.

For a better understanding of my invention reference may be had to the accompanying drawing which is a schematic representation of a circuit breaker and control therefor comprising the essential features of my invention.

10. In the drawing there is illustrated an electric circuit interrupting device generally indicated at 1 for controlling a circuit comprising conductors 2 and 3 to which contacts 4 and 5 are connected. Bridging member 6 is supported by operating rod 7 on which is mounted a projecting portion 8. A latch 9 is pivotally supported on a stationary pin 10. Latch 9 is provided with the projection 11 which cooperates with the projection 8 on rod 7 to hold the circuit breaker closed as shown in the drawing. Latch 9 may be provided with a projection 12 for receiving the tripping force as will be more clearly understood as the description proceeds. A relatively light compression spring 13 may be used to bias the latch 9 toward the latching position. An arm 14 is pivotally mounted at one end thereof on a stationary pin 15. Arm 14 may be constructed with an enlarged portion such as is indicated at 16 in the drawing. The enlarged portion 16 of arm 14 comprises an impact member for operating the latch 9. Preferably, although not necessarily, arm 14, latch 9 and circuit breaker supporting rod 7 will be constructed of metal. Positioned adjacent the enlarged portion 16 of arm 14 in engaging relationship therewith is a relatively long rod or impulse transmitting member 17 which, preferably, should be constructed of insulating material such as impregnated wood, resinous material or the like. Insulating rod 17 is supported within a cavity 18 in base member 19 and suitable supports such as 20 may be provided. Constructed within base member 18 is an opening 21.

In order to generate a percussion wave in the insulating rod 17, it is necessary to provide means for striking the lower end of rod 17. Of course, this particular function may be accomplished in any suitable manner such as by moving a mass at relatively high velocity by means of fluid pressure or by mechanical means or by electromagnetic means utilizing a source of low voltage power. I have chosen to illustrate the percussion wave generating means as an electrically operated mechanism comprising the solenoid 22 in which is mounted an armature or percussion

3
plunger 22. Current is supplied to coil 21 from a source of electric power, not shown, through manually operable switch 23 and leads 24. It will be obvious to those skilled in the art, that automatically operable means could be substituted for the manually operable switch 23 such as for instance a current transformer mounted around either conductor 2 or conductor 3 which transformer would supply a controlling current to a relay which, in turn, could operate the control circuit to solenoid 21.

When the circuit to solenoid 21 is completed as by closing switch 23, percussion member 22 will be lifted upwardly and tip 25 of percussion member 22 will pass through opening 20 of base member 18 and upon the engagement of tip 25 with the end surface 26 of rod 16 the upward movement of percussion plunger 22 will be arrested. The arresting of the upward motion of percussion plunger 22 will impart to insulating rod 16 a high speed high energy mechanical impulse which will traverse rod 16 at substantially the speed at which sound would traverse the rod without causing substantial bodily movement of rod 16. As is well known, the speed at which the wave travels depends upon the characteristics of the material chosen for rod 16. When the impulse wave reaches the upper end of rod 16 its energy will be imparted to arm 13 through enlarged portion 15 thereof whereupon arm 13 and its enlarged portion 15 will move counterclockwise about the stationary pivot 14. Movement of rod 13 results in the engagement of enlarged portion 15 of rod 13 with the projection 12 of latch 9, thus causing projection 11 of latch 9 to release the projection 8 of supporting rod 7. Upon release of the latching mechanism, the circuit breaker bridging member 6 is free to travel downwardly under the influence of gravity or, as might be desirable, under the pressure of biasing springs which are not shown in the drawing.

For the purpose of regulating the speed of transmission of the impulse wave, it is only necessary to change the mass of the enlarged portion 15 of arm 13. By increasing that mass, the speed of transmission of the impulse to latching arm 9, may be decreased. Furthermore, the magnitude of the percussion may be varied by adjusting the current supplied to solenoid 21 when switch 23 is closed.

It may be desirable to cause a number of circuit breakers incorporating my invention to operate synchronously or to operate at intervals. Thus it will be apparent that my invention is readily adaptable either to a single circuit breaker acting individually or to two or more circuit breakers forming a part of an integral power system.

Having shown and described a particular embodiment of my invention it will be obvious to those skilled in the art that various changes and modifications may be made without departing from my invention and I, therefore, intend in the appended claims to cover all such changes and modifications as fall within the true spirit and scope of my invention.

What I claim as new and desire to secure by Letters Patent of the United States is:

1. A mechanical impulse mechanism for imparting actuating force to the operating means of an electric circuit breaker comprising a movable plunger, means for imparting motion to said plunger, an impulse transmitting rod member of insulating material disposed in the path of

movement of said plunger and normally in spaced relation thereto in which a high speed percussion impulse wave is generated by the collision of said plunger with one end of said rod, and a movable impact member normally engaging the other end of said rod and movable in response to an impulse wave traveling longitudinally therein for imparting actuating force to the operating means of said circuit breaker.

10 2. A device for controlling the operating means of a high voltage electric circuit breaker from a low voltage source of power comprising a percussion plunger movable in response to current from said low voltage source, a movable impact member for imparting controlling force to said operating means, and impulse transmitting means of insulating material interposed between said percussion plunger and said impact member for arresting the movement of said plunger thereby to establish a high speed impulse wave in said transmitting means, said impulse wave being for the purpose of initiating bodily movement of said impact member in substantially the time required for sound to travel through said impulse transmitting means after the collision between said plunger and said impulse transmitting means for controlling said circuit breaker.

30 3. A mechanism for imparting activating force to the mechanical tripping mechanism of a high voltage electric circuit breaker comprising a source of low voltage power, a movable percussion plunger, electromagnetic means responsive to current from said low voltage power source for imparting bodily movement to said plunger, a movable impact member for activating said mechanical tripping mechanism, and a rod of insulating material coaxially disposed with respect to said plunger and said impact member for transmitting to said impact member the 40 percussion impulse wave generated in said rod by the collision of said plunger and said rod thereby to trip said circuit breaker.

45 4. An electric circuit breaker comprising relatively movable contacts biased to the open position, latching means for holding said contacts in the closed position, a movable impact member for tripping said latching means, and means for imparting tripping movement to said impact member including an impulse transmitting member having a portion thereof in engagement with said impact member and means for causing an impulse percussion wave to travel through said transmitting member for imparting movement to said impact member to release 55 said latching means and thereby to open said circuit breaker.
